UNITED STATES PATENT OFFICE.

GEORGE H. RIVES, OF NEW YORK, N. Y.

PEDAL-PAD.

1,243,764.

Specification of Letters Patent.

Patented Oct. 23, 1917.

Application filed March 24, 1917. Serial No. 157,176.

To all whom it may concern:

Be it known that I, GEORGE H. RIVES, a citizen of the United States, and a resident of New York, county and State of New York, have invented a certain new and useful Improvement in Pedal-Pads, of which the following is a full, clear, and exact specification.

This invention relates more particularly to a class of devices adapted to be used on automobiles, and has for its object primarily to provide a pad, or cushion designed to be applied on the foot pedal of the accelerator, or brake mechanism of a vehicle where-by the foot of a person may be prevented from tending to slip from the pedal when moved to operate the accelerator, or brake mechanism, and which is susceptible of being made in different sizes and shapes so as to be effectually used on pedals of various types. This is accomplished mainly by providing a cushion, or resilient pad adapted to be applied on the pedal, and extending through the cushion may be one or a number of pliable metallic strips of lengths so that their ends protrude beyond the cushion for being bent into engagement with the pedal for removably attaching the cushion thereon.

Other objects of the invention are to provide one or a number of projecting gripping members, or buttons on each strip so as to be embedded in or to engage the pad; and to provide on one or more parts of each strip a series of teeth to cause the cushion to adhere thereto whereby the cushion will be prevented from tending to slip on the strip.

A practical embodiment of the invention is represented in the accompanying drawing forming a part of this specification in which similar characters of reference indicate corresponding parts in all the views, and will then be pointed out in the claims at the end of the description.

In the drawing, Figure 1 is a fragmentary view, showing a side elevation of a foot pedal with one form of the device embodying my invention applied thereon.

Fig. 2 is a top plan of the device.

Fig. 3 is a section taken on the line III—III of Fig. 2.

Fig. 4 is a top plan of a different form of the device.

Fig. 5 is a section taken on the line V—V of Fig. 4, and

Fig. 6 is an edge view of one of the metallic strips employed in the device.

The device has a cushion, or pad 10 made of rubber, or other material so as to yield under the pressure of a person's foot, and the pad may be of any suitable thickness as well as being of any desired shape to conform with the shape of various types of the foot pedals, as 11, of the accelerators, or brake mechanisms of automobiles.

In Figs. 1, 2, 3 the pad 10 is shown as being substantially rectangular, and to detachably fasten the pad on a foot pedal a number of pliable metallic strips, as 12 and 13, may be employed. When the pad is made of rubber these strips are embedded therein during its molding process so as to be disposed transversely through spaced parts of its center, and both strips are of lengths so that their ends protrude some distances beyond the opposite edges lengthwise of the pad.

In order to hold the strips 12 and 13 in the pad, or cushion against accidental displacement as well as tending to prevent the pad from slidably moving thereon, one or a number of gripping members, as 14 and 15, are provided on each of the strips. These gripping members may be in the forms of buttons, or knobs, or pins projecting preferably upwardly from spaced parts of the top faces of the strips, and these gripping members may be integral with each strip, or the members may be separately formed and fastened on the strips. When the pad with the holding strips are molded these gripping members, or buttons will also be embedded in the pad, and to further prevent the pad from tending to slidably move accidentally on the strips under the pressure of the foot of a person, projecting from part of the top surface as well as extending from a portion of the underside of each strip are a series of small teeth 16 and 17 which are also embedded in the pad for causing it to adhere to the strips.

In Figs. 4 and 5 the pad, or cushion 10 is illustrated as being approximately oval in shape, and serving to permit this pad to be removably fastened on a foot pedal, a holding element, as 18, is provided. The holding element 18 is preferably in the form of integral strips, of pliable metal arranged in substantially the shape of a cross to provide four arms 19, 20, 21, 22, and this element is embedded in the pad so that its arms extend

radially through the edge of the pad as well as being of lengths so that their ends protrude some distances beyond the pad.

This oval pad, or cushion 10 is held against accidental movement on the strip by providing a number of gripping members 23, 24, 25, 26 all of which may be in the forms of buttons, or knobs, or pins similar to the gripping members of the device, shown in Figs. 1, 2, 3, and one of the members extend upwardly from each of the arms of the holding element 18 as well as being embedded in the pad. To also cause the pad to adhere to element 18 the top surface and the underside of the adjacent parts of the arms of this element are respectively provided with projecting teeth, as 27 and 28, which may be similar to the teeth of the pliable holding strips of the form of the device indicated in Figs. 1, 2, 3, and these teeth 27 and 28 are sunken in the pad when made of rubber during the process of being molded.

In order to apply the device to the foot pedal of the accelerator, or brake mechanism, of an automobile the pad 10 is disposed on the top of the plate of the pedal so that the protruding ends of the holding strips overhang the plate. These ends of the strips are then bent over the edge of the plate so as to engage its underside, and the pad will then be detachably clamped on the pedal for use to prevent the foot of the chauffeur from tending to slip from the pedal when operating the accelerator, or brake mechanism.

In the foregoing description, I have embodied the preferred form of my invention, but I do not wish to be understood as limiting myself thereto, as I am aware that modifications may be made therein without departing from the principle, or sacrificing any of the advantages of this invention; therefore I reserve to myself the right to make such changes as fairly fall within the scope thereof.

Having thus described my invention, I claim as new and desire to secure by Letters Patent—

1. In a device of the character described, a cushion adapted to be applied on a pedal, a pliable metallic strip protruding from the cushion for being bent so as to engage the pedal to releasably hold the cushion thereon, and a gripping element projecting from one

face of the strip into the cushion for securing the strip therein. 55

2. In a device of the character described, a cushion adapted to be applied on a pedal, a plurality of pliable metallic strips protruding from the cushion for being bent so as to engage the pedal to releasably hold the cushion thereon, and spaced buttons on each strip projecting into the body of the cushion for securing the strips therein. 60

3. In a device of the character described, a rubber pad adapted to be applied on a pedal, a pliable metallic strip embedded in the pad with parts protruding from the pad for being bent so as to engage the pedal to releasably hold the pad thereon, and teeth projecting from the strip into the body of the pad for securing the strip therein. 65

4. In a device of the character described, a rubber pad adapted to be applied on a pedal, a plurality of pliable metallic strips embedded in the pad with parts protruding from the pad for being bent so as to engage the pedal to releasably hold the pad thereon, and teeth projecting from each of the strips into the body of the pad for securing the strips therein. 70

5. In a device of the character described, a rubber pad adapted to be applied on a pedal, a pliable metallic strip embedded in the pad with parts protruding from the pad for being bent so as to engage the pedal to releasably hold the pad thereon, spaced knobs projecting from one face of the strip into the body of the pad for securing the strip therein, and teeth on the strip embedded in the body of the pad. 75

6. In a device of the character described, a rubber pad adapted to be applied on a pedal, a plurality of pliable metallic strips embedded in the pad with parts protruding from the pad for being bent so as to engage the pedal to releasably hold the pad thereon, spaced knobs projecting from one face of each strip into the body of the pad for securing the strip therein, and teeth on the top and underside of each strip embedded in the body of the pad. 80

This specification signed and witnessed this 23rd day of March, A. D. 1917.

GEORGE H. RIVES.
